Primary Examiner — Patricia A Palasik(74) *Attorney, Agent, or Firm* — Richard L. Miller(57) **CLAIM**

The ornamental design for a vertical seam welder component, as shown and described.

DESCRIPTION

FIG. 1 is a perspective view of a vertical seam welder component showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof; and,

FIG. 7 is a view identical to FIG. 1 with descriptive legend directional arrows included which are necessary for better understanding of the drawing.

Any portion of the claimed design that is shown separated and bound by a bracket indicates that no particular length is being claimed and any portion of the article between the break lines forms no part of the claimed design. A view of the bottom is omitted because the bottom is flat and devoid of surface ornamentation.

1 Claim, 5 Drawing Sheets---
